UNITED STATES PATENT OFFICE.

IRVING R. PARSONS, OF CHICAGO, ILLINOIS.

DESIGN FOR A RECEPTACLE.

58,254.

Specification for Design. Patented June 28, 1921.

Application filed November 29, 1920. Serial No. 427,243. Term of patent 14 years.

To all whom it may concern:

Be it known that I, IRVING R. PARSONS, a citizen of the United States, residing at Chicago, in the county of Cook and State of Illinois, have invented a new, original, and ornamental Design for Receptacles, of which the following is a specification, reference being had to the accompanying drawing, forming part thereof.

Figure 1 is a plan of the receptacle.

Fig. 2 is a side elevation of the same.

I claim:

The ornamental design for a receptacle as shown.

IRVING R. PARSONS.
